E. W. PALMQUIST.
SIDE FRAME AND JOURNAL BOX.
APPLICATION FILED NOV. 28, 1914.

Patented June 22, 1915

UNITED STATES PATENT OFFICE.

ERIC W. PALMQUIST, OF ST. LOUIS, MISSOURI, ASSIGNOR TO AMERICAN STEEL
FOUNDRIES, OF NEW YORK, N. Y., A CORPORATION OF NEW JERSEY.

SIDE FRAME AND JOURNAL-BOX.

1,143,723.

Specification of Letters Patent. Patented June 22, 1915.

Application filed November 28, 1914. Serial No. 874,521.

To all whom it may concern:

Be it known that I, ERIC W. PALMQUIST, a citizen of the United States, residing at St. Louis, State of Missouri, have invented 5 certain new and useful Improvements in Side Frames and Journal-Boxes, of which the following is a specification.

My invention relates to car trucks and has particular reference to a novel attaching device for use between the frame and journal box.

In car trucks, as now commonly constructed, the side frame members are cast in a single piece and are frequently provided 10 with jaws or pedestals at their ends between which jaws a journal box is fitted. This provides against separation in lateral directions, but it is preferable that means should be provided to prevent possible accidental 15 separation in a vertical direction. Preferably such means should be of a simple character and inclosed in such manner as to avoid injury and deterioration. Cheapness and simplicity in construction are essential 20 elements in such a device and it is thought the desirable features heretofore mentioned are secured in the construction here disclosed.

The invention will be more readily understood by reference to the accompanying drawings in which,

Figure 1 is a side elevation of a fragment of a car truck side frame and journal box, the journal box being shown in section; Fig. 35 2 is a plan view thereof; Fig. 3 is a section on the line 3—3 of Fig. 1; Fig. 4 is a view similar to Fig. 1, showing a slightly modified construction; and Fig. 5 is a section on the line 5—5 of Fig. 4.

Referring more particularly to the drawings, it will be seen that a side frame 10 may include jaws 11, between which a journal box 12 is seated. As shown in Fig. 2, the journal box may be provided with lateral 40 lips or guides 13 between which the box is fitted. By this means the box is held against separation in a sidewise or endwise direction, but is not held against vertical separation. In order to provide against this contingency I cast on the top of the journal box a boss 14 hollowed out as at 15 to accommodate the head of a vertical bolt or pin 16. This bolt or pin extends upwardly through an aperture 17 in the side frame and may be held

by means of a key 18 inserted through an 55 opening 19 in the web of the side frame. In practice the bolt 16 is inserted within the hollow boss 14 of the journal box and the box then locked in the position shown in Fig. 1. When in this position the bolt cannot be moved in a lateral direction. In the construction shown in Figs. 4 and 5, the journal box 20 is provided with a boss 21 on its upper surface an opening being formed therethrough for the passage of a bolt or pin 22. This bolt is insertible through the inside of the journal box, the head of the bolt being countersunk in the enlarged recess 23. The bolt is held by means of a key 24 as shown in Figs. 1 to 3. If desired, of course, a nut may be substituted for the key shown in each construction. The space 25 surrounding the boss 21 is provided merely for the purpose of lightening the construction. This is likewise true in the form shown 75 in Fig. 1.

An advantage in the construction shown herein is that the bolt is almost entirely inclosed and cannot become disengaged by accident or without lifting the frame sufficient 80 to disengage the journal box therefrom.

Obviously the construction shown is capable of considerable modification and such modification as is within the scope of my claims I consider within the spirit of my invention.

I claim:

1. In a truck, the combination of a side frame, a journal box, said frame having an aperture in the plane of said box, and a 90 separate vertical bolt carried by said box and adapted to coöperate with said aperture and maintain said box and frame against separation, substantially as described.

2. In a truck, the combination of a cast 95 side frame, a journal box interlocked with said frame, and a separate vertical bolt connecting the frame and box, substantially as described.

3. In combination, a cast side frame having jaws, a journal box mounted between said jaws, a vertical bolt interlocked with said journal box, said bolt extending upwardly through an aperture in said frame, and means carried by said bolt for locking 105 the same in position.

4. In combination a cast side frame having jaws, a journal box mounted between

said jaws, said box being provided with an apertured boss, a bolt the head of which is mounted in said boss, said bolt extending upwardly through an aperture in said frame 5 and securing said box and frame against separation, substantially as described.

In witness whereof I have hereunto signed

my name in the presence of two subscribing witnesses.

ERIC W. PALMQUIST.
